UNITED STATES PATENT OFFICE.

CHARLES E. SMITH, OF CHICAGO, ILLINOIS.

OIL BURNER.

Application filed February 5, 1927. Serial No. 186,141.

This invention relates to improvements in oil burners and its chief object is to provide an oil burner designed for use in heating plants for homes, apartments and other buildings although it is susceptible of a variety of other uses.

A further object is to provide an oil burner wherein dry steam is used to superheat the oil previous to combustion of the same, this steam then being mixed with the oil stream at its point of combustion.

A further object is to provide an oil burner of this type wherein means are provided for generating the steam used. A further object is to provide a burner that does not form carbon.

A still further object is to provide an oil burner that is dependable and efficient in use, safe in operation and that will burn ordinary fuel oil as well as any or all of the refined or lighter oils in a thoroughly satisfactory and economical manner and with the maximum production of heat.

With the foregoing and other objects in view the invention consists in the combination and arrangement of parts to be herein-after fully described, pointed out in the appended claims and illustrated in the accompanying drawings which form a part of this application and in which—

Fig. 1 is a sectional view of a hot water boiler illustrating the application of the oil burner.

Fig. 2 is a view in front elevation of the fuel supply and control mechanism.

Fig. 3 is a horizontal sectional view taken on line 3—3 of Fig. 2.

Fig. 4 is an enlarged fragmentary sectional view of the fuel delivery nozzle.

Fig. 5 is a cross section, enlarged, on line 5—5 of Fig. 7.

Fig. 6 is an enlarged sectional view of a type of control valve employed.

Fig. 7 is an enlarged sectional view of the generator and the fuel supply mechanism.

Like reference characters denote corresponding parts throughout the several views.

The present burner comprises a steam generator wherein water under pressure, as water supplied by the water mains of any large city, is admitted and turned into steam by the application of heat direct to the generator either by means of a gas pilot light or by the combustion of the fuel after the burner is in operation, and the steam so formed is used to preheat the oil stream just previous

to its combustion, the dry steam after pre-heating the oil being directed, under considerable pressure, into the oil stream and mixed therewith during combustion. Means are provided for automatically controlling the amount of dry steam to be mixed with the oil stream, or vapor, and for automatically controlling the supply of water to the generator.

The reference numeral 1 denotes a hot water boiler provided with the usual door 2 and grate 3. A standard 4 is supported in a floor casting 5 as a support for an oil supply pipe 6, a water pipe 7 and a gas pipe 8 each of which pipes leads to a supply source and is provided with a hand control valve 9. The gas pipe 8 is connected by union 10 with a flexible gas pipe 11 that is connected, by means of a union 12 provided with a hand valve 13, to the gas service pipe comprising the sections 14, 15 which are connected by the union 16 provided with a valve 17, the gas pipe section 15 being supported by the bracket 18 carried by the door 2, and a gas pilot pipe 19 communicating with the said pipe section 15 to supply the forked gas pilot 20, the prongs of which are disposed upon opposite sides of the generator casing 21.

The water pipe 7 is connected by union 22, provided with a cut-off valve, with a flexible water pipe 23 that is connected, by means of a union 24, provided with a hand valve 24^a, to a water delivery pipe comprising the three sections 25, 26, 27, the sections 25, 26 being connected by the T-union 28 which communicates with and connects said pipe sections to the water diaphragm 29 the flexible membrane 30 of which is adapted to actuate a plunger 31 disposed immediately beneath said membrane, the lower end of said plunger being slidably disposed in the lower tubular end of the diaphragm casing wherein the longitudinal slot 32 is formed through which, and through the plunger, a rod 33 extends that is carried by said plunger, the ends of said rod being connected to the levers 34, 35, each of which is fulcrumed upon a pin 36 carried by a bracket 37 through which the stem of a valve 17 extends for operative engagement with the free end of a lever 34 or 35, one bracket 37 being secured to one union 16 and a similar bracket being likewise secured to the union 38. The levers 34, 35 are identical in their construction, operation and function and the illustration in Fig. 6 is deemed sufficient as one assembly is here illustrated.

100
105
110

The said union 38 connects pipe sections 39, 40, the latter section being connected by the valved union 41 to a pipe section 42 which is connected by means of a valved 5 union 43, provided with a hand valve 44, to the flexible oil pipe 45 that is connected by a union 46, provided with a cut-off or safety valve, with the oil pipe 6. Referring again to the pipe section 39 the same is connected 10 to an oil pipe 47 that is connected by the interiorly threaded coupling 48 to the exteriorly threaded tubular link 49 that is adjustably connected to the link coupling 50 and movable inwardly or outwardly relative 15 thereto, said tubular link 49 having secured thereto by screws 49^a the control lever 51.

The link coupling 50 is carried by the exteriorly threaded tubular extension 52 of the dry steam chamber 53, dome shaped and 20 formed with the elongated tubular nozzle portion 54 in the plane of the tubular extension 52 and having its free end tapered or beveled to form a discharge opening 55. Extending through the nozzle portion 54, chamber 53 and extension 52 and of considerably 25 smaller diameter than any of these members so that a space is formed thereabout is the oil delivery pipe 56 that extends also through the coupling 50 and is terminally threaded 30 to permit it to be screwed into engagement with the interiorly threaded end of the tubular link 49, a collar 57 extending about said pipe 56 closing the space between the same and the tubular extension 52 at the outer end 35 of said member. The free end of the said oil pipe 56 is tapered and disposed in the discharge opening 55 of the nozzle 54, said pipe being adapted for movement longitudinally of said nozzle, dome 53 and extension 40 52 upon oscillation of the said lever 51 so that its tapered end serves to regulate the discharge of steam or water through said discharge opening by closing to a greater or lesser degree the said opening. The free ends 45 of members 54, 56 are so tapered relatively that the space therebetween may be completely-closed when desired. A collar bushing 58 is interposed between and carried by said oil pipe and nozzle adjacent their tapered ends 50 and serves to fill the space between said members at this point, and to center said oil pipe in said nozzle, said collar being formed with a plurality of spaced longitudinally extending perforations 59 to at all times permit 55 the passage therethrough of a certain amount of steam or a very limited amount of water.

Referring again to the dry steam chamber 53 the same is disposed upon and secured to a moist steam chamber 60 provided with a 60 blow off valve 61 and with a drain cock 62, said dry and moist steam chambers being made intercommunicating through the medium of the tubular connection 63, said steam chamber 60 having secured thereto 65 and communicating therewith the open end

of the generator shell 21 within which is the insert shell 65 which is spaced away from the said shell 21, the inner open end of said insert shell being spaced away from the closed end 66 of the shell 21, the outer 70 end of said insert shell extending slightly beyond the open end of said shell 21 and being perforated to receive the water pipe 27 that extends the entire length of said shell 65, said insert shell being spaced away therefrom and from the shell 21 by means of the spacer rivets 67.

Referring again to the control lever 51 the same is connected at one end by a link 68 to the rod 69 that opens, closes and controls the 80 check valve 70 that regulates the flow of oil through the union 41, said lever 51 at its opposite end being connected by the chain 71 and cable 72 to the motor box 73 of the room thermostat (not shown). A counterbalance 85 weight 74 is also carried by the lever 51 at the same end as that engaged by the chain 71 and a take-up chain 75 also connects said lever 51 and a collar 76 arranged upon the pipe link 15 and any one of the links of said 90 chain 75 may be engaged by the hooked end of the collar 76 so that the extreme distance possible between the lever 51 and said collar may be regulated thereby. In this manner the arc of oscillation of the lever 51 may be limited as desired thus enabling one to so set the said lever as to cause it to control the valve 70 with precision. A water-temperature thermometer 77 and a manometer 78 are 95 operatively connected to the pipe 25.

In operation it will first be assumed that the device is to be started for the first time, either at the beginning of the heating season or after first installation. At the time of this starting or previous thereto the room thermostat indicator is positioned at a low temperature point, such as 50 degrees Fahrenheit. The control lever 51 actuated by the weight 74 has closed the space between the tapered ends of the members 54 and 56. The 105 water valve 24^a is now opened full thus permitting water from the source to flow through pipes 7, 23, through the open valve in the union 24, through pipe section 25 and union 28 into the diaphragm 29, through pipe 110 sections 26, 27 into the generator shells 21, 65, into the moist steam chamber 60, dry steam chamber 53 and nozzle 54 but escape of water from the discharge end of said nozzle or through the tubular extension 52 beyond the 115 collar 57 is now impossible.

The gas valve 13 is now opened in full and the pilot lit. The gas flame playing about the generator shell 21 will generate steam therein and this steam will pass from the generator into the chamber 60 and then into the chamber 53 and force back the water therefrom. When the thermometer 77 shows approximately 220 degrees Fahrenheit or the manometer shows approximately 20 pounds pres- 120 125 130

sure the oil valve 44 is opened to a "running point" denoted upon one end face of the union 43 in connection with a notch or indicator upon the stem leading from the hand wheel 44 into said union. This "running point" is ascertained by factory test and is communicated to the user at the time of installation. The room thermostat is now set at the room temperature desired, as 70 degrees Fahrenheit, the gas valve 13 partly shut off or disposed in "running position" which is determined and denoted in a manner similar to that described with relation to the oil valve and the burner is in operation and is "set" for the season. When the room temperature rises above 70 degrees, or any other set temperature, the thermostat will, in a well known manner, permit the control lever 51 with its weight 74 to shut off the oil supply at the valve 70, and to close the space between the discharge ends of the oil pipe 56 and nozzle 54. When the room temperature drops below 70 the mechanism will be started up again.

When the control lever turns on the oil in full it also causes a movement of the oil pipe 56 relative to the nozzle 54 so that their tapered ends are spaced apart and the steam from the generator passing through the chambers 60, 53 will pass through the nozzle 54, through the perforations 59 in the collar 58 and out into the oil stream from the pipe 56. This oil has been preheated by the hot steam in the chamber 53 encircling the pipe 56 and in such state it is highly combustible. The steam passing with great force from the nozzle discharge port causes a partial vacuum at this point which sucks the oil from the pipe 56 which suction is quite sufficient to draw the oil from a supply tank at any desired position. The oil and steam come together about the gas flame and the oil is broken up and this gaseous fuel burns with an intense heat, never less than 900 degrees Fahrenheit, about the generator outer shell providing heat for generating steam from the water constantly supplied to that member.

Combustion of the fuel begins at a point slightly in advance of the tapered end of the nozzle 54 and it will be noted that this member is so located and disposed relative to the generator shell and pilot that the burning fuel envelops the generator. When the burner is shut down for the night or between periods of operation the pilot will keep up steam which steam will always have the oil in the pipe 56 preheated and ready at the instant the thermostat sets the mechanism in operation again. Should the pilot light go out or be put out for any reason and the thermostat be in position to cause operation of the burner the steam generated previous to the extinguishing of the pilot will soon be used up and the water will then pass from the

generator into the chambers 60 and 53 and then into the nozzle 54 from the discharge port of which the water will trickle, mixed with oil from the pipe 56, down upon the generator casing and off into the overflow 70 pan 79 located upon the grate 3 and from said pan it will pass through the pipe 80 into the trip bucket 81 suspended by the chain 82 which is operatively connected to the emergency or cut-off valves 22, 46 which will cut off the supply of water and oil. The escape of gas from the pilot will not be enough to become a menace because the water pressure in the diaphragm has ceased and the rod 33 will cause the rods 34, 35 to abate pressure 80 against the stems of the valves 17 thus permitting the valve springs 17^a to close the valves, cutting off the gas. The oil valve in union 38 will be closed in like manner. If the water is cut off while the pilot is burning 85 the water pressure in the diaphragm will abate and gas and oil be cut off.

What is claimed is:—

1. In an oil burner, a heated steam generator, means for supplying water under pressure to said generator, a moist steam chamber communicating with said generator, a dry steam chamber communicating with said moist steam chamber, a nozzle for said dry steam chamber, an oil pipe disposed longitudinally and adjustably of said nozzle and dry steam chamber, the discharge terminals of said nozzle and oil pipe being capable of contact one with the other, a collar bushing connecting said nozzle and oil pipe, and thermostatic control mechanism for effecting the adjustment of said oil pipe and for regulating the supply of oil to said oil pipe.

2. In an oil burner, a heated steam generator, means for supplying water under pressure to said generator, a moist steam chamber communicating with said generator, a dry steam chamber communicating with said moist steam chamber, a nozzle for said dry steam chamber, an oil pipe disposed longitudinally and adjustably of said nozzle and dry steam chamber, the discharge terminals of said nozzle and oil pipe being capable of contact one with the other, a perforate collar connecting said nozzle and oil pipe, and thermostatic control mechanism for effecting the adjustment of said oil pipe and for regulating the supply of oil to said oil pipe simultaneously with said pipe adjustment.

3. In an oil burner, a gas heated steam generator, water supply means for said generator, superposed steam chambers communicating with each other and with said generator, a nozzle communicating with one of said steam chambers and having its discharge port located above and contiguous to said steam generator, an oil supply pipe disposed within and adjustable longitudinally of and spaced from the last named steam chamber and the said nozzle, the discharge ports of

said nozzle and oil pipe being capable of contact one with the other by adjustment of said oil pipe, and thermostatic control mechanism for effecting the said oil pipe adjustments 5 and for regulating the supply of oil to said pipe.

4. In an oil burner, a gas heated steam generator, water supply means for said generator, superposed steam chambers communicating with each other and with said generator, a nozzle communicating with one of said steam chambers and having its discharge port located immediately above said steam generator, an oil supply pipe disposed within and 10 adjustable longitudinally of and spaced from the last named steam chamber and the said nozzle, the discharge ports of said nozzle and oil pipe being capable of separable contact one with the other by adjustment of said oil 15 pipe, a perforate ring interposed between the said nozzle and oil pipe and fixed to the later, adjacent the discharge terminals thereof, and thermostatic control mechanism for effecting the said oil pipe adjustments and for regulating 20 the supply of oil to said pipe correspondingly.

5. In an oil burner, a steam generator, superposed steam chambers communicating with each other and with said generator, a 30 nozzle communicating with one of said chambers and disposed immediately above and inclined toward said steam generator, a pilot for said generator, an oil supply pipe extending longitudinally of and adjustable with relation to said nozzle and one of said steam chambers, the discharge ports of said oil 35 pipe and nozzle being capable of separable contact one with the other as said oil pipe is adjusted, and thermostatic control mechanism for effecting the said oil pipe adjustments and for regulating the supply of oil to said pipe to correspond to said pipe adjustments.

6. In an oil burner, a steam generator, a 40 water supply line therefor, a water pressure diaphragm in said line, intercommunicating steam chambers communicating with said generator, a pilot light for said generator,

a nozzle integral with one of said steam chambers and disposed immediately above and inclined toward said generator, an adjustable oil supply pipe extending longitudinally of said nozzle and of one of said steam chambers and spaced away from said members, the discharge ports of said oil pipe and nozzle 50 being capable of separable contact one with the other as said oil pipe is adjusted, a perforate ring connecting said oil pipe and nozzle adjacent the discharge ports of said members, a valved oil supply line communicating with said oil pipe, a valved gas line communicating with said pilot, valve control mechanism connecting said diaphragm and the valves in said gas and oil lines, and thermostatic control mechanism for effecting the 55 said oil pipe adjustments and for regulating the supply of oil to said oil pipe to correspond to said pipe adjustments.

7. In an oil burner, a steam generator, a water supply line therefor, a water pressure 70 diaphragm in said line, superposed intercommunicating steam chambers communicating with said generator, a pilot for said generator, a gas line for said pilot, means connecting said water diaphragm and gas 75 line whereby the flow of gas therethrough is regulated by said diaphragm, a nozzle integral with one of said steam chambers and communicating therewith, an oil pipe within said nozzle and spaced from the wall thereof 80 and adjustable with relation thereto, the discharge ports of said nozzle and oil pipe being capable of separable contact one with the other, a perforate collar bushing connecting said oil pipe and nozzle adjacent their discharge ends, an oil supply line for said oil pipe, connection between said water diaphragm and oil line whereby the flow of oil 85 therethrough is controlled by said diaphragm, and thermostatic control mechanism for effecting the adjustment of said oil pipe and for regulating the flow of oil through said oil line to correspond to said adjustment.

In testimony that I claim the foregoing as my own I have hereto affixed my signature.
CHAS. R. SMITH.
